FIG. 12

UNITED STATES PATENT OFFICE.

JAY G. THOMAS, OF PHILADELPHIA, PENNSYLVANIA.

SUSPENDED FURNACE-ROOF.

1,372,848.

Specification of Letters Patent. Patented Mar. 29, 1921.

Application filed April 3, 1919. Serial No. 287,240.

To all whom it may concern:

Be it known that I, JAY G. THOMAS, a citizen of the United States, residing at the city of Philadelphia, county of Philadelphia, and 5 State of Pennsylvania, have invented certain new and useful Improvements in Suspended Furnace-Roofs, of which the following is a specification.

This invention, generally stated, relates to 10 boiler and heating furnaces of various types and has more particular relation to a suspended, flat roof therefor.

An object of the present invention is to 15 provide a suspended, flat roof construction which is equally well adapted for old and new furnace installation and which permits of ready removal and replacement of tiles, separately, by unskilled labor and which further permits, in the case of breakage of 20 tile supporting elements, repair of same without removal of any considerable number of tiles. Another object is to provide a suspended, flat roof construction possessed of 25 flexible characteristics whereby stress and strain, due to expansion and contraction, is reduced to a minimum thus eliminating spalling or cracking of the working faces of the tiles. A further object is to provide a suspended, flat roof construction in which is 30 embodied novel devices for supporting those tiles in immediate juxtaposition to the curtain wall of a furnace. A still further object is to provide a suspended, flat roof construction which is of simple, comparatively in- 35 expensive, practical and efficient structure whereby the commercial value of a furnace roof construction, of the character under consideration, is materially enhanced over like constructions now in use. Other and 40 further objects relate to the provision of certain combinations, arrangements and connections of parts as will hereinafter be more fully set forth.

The invention consists of the improvements hereinafter described and finally claimed.

The nature, characteristic features and scope of the invention will be more fully understood from the following description 50 taken in connection with the accompanying drawings forming part hereof, and in which:

Figure 1, is a view in longitudinal section of a portion of a furnace illustrating the 55 suspended, flat roof embodying features of the invention in application thereto.

Fig. 2, is a view in transverse section taken upon the line 2—2 of Fig. 1.

Fig. 3, is a fragmentary view illustrating in detail the manner of suspending a tile. 60

Figs. 4 and 5, are front and side elevational views respectively, showing the manner of introducing a hanger through the slotted top of a tile, parts of the tile being broken away for illustrative purposes. 65

Fig. 6, is a top or plan view thereof illustrating the hanger moved around its vertical axis 90° to interlocking position.

Fig. 7, is a fragmentary view in section illustrating a modified form of hanger support. 70

Fig. 8, is a similar view of a modified form of hanger and hanger support.

Fig. 9, is a fragmentary view in cross-section of a modified form of tile support. 75

Fig. 10, is a view in side elevation of the tiles and support shown in Fig. 9.

Fig. 11, is a fragmentary view in section illustrating the manner of suspending those tiles immediately adjacent a furnace curtain 80 wall.

Fig. 12, is a top or plan view of certain of the parts shown in Fig. 11, and

Fig. 13, is a view in rear elevation of certain of the parts shown in Figs. 11 and 12. 85

For the purpose of illustrating my invention, I have shown in the accompanying drawings forms thereof which are at present preferred by me, since the same have been found in practice to give satisfactory and 90 reliable results, although it is to be understood that the various instrumentalities of which my invention consists can be variously arranged and organized and that my invention is not limited to the precise arrangement 95 and organization of the instrumentalities as herein shown and described.

For illustrative purposes I have shown my improved suspended, flat roof construction as applied to a boiler furnace of the type in 100 which a traveling grate-stoker is employed although obviously the roof of the invention is applicable to various types of furnaces. Generally stated the roof comprises a plurality of individually separable tiles so suspended 105 that the under surface thereof is transversely parallel with the bed or floor of the furnace as shown in Fig. 2, but preferably has a variable distance from the furnace bed in a longitudinal direction as shown in Fig. 1. 110 By so suspending the tiles, a uniform area is maintained across the furnace and a pro-

gressively increasing area is maintained longitudinally of the furnace which increasing area is advantageous in that heated gases have ample space for freedom of movement as they pass toward the rear of the furnace. In the drawings 10 designates the furnace firebox, 11 a traveling grate-stoker (indicated by broken lines), and 12 the furnace side walls. Supported by the side walls of the furnace and extended transversely, of the furnace above the grate are standard channel irons 13, spaced apart by means of plates 14, bolts 15 being employed to secure the parts together to form beams. A. In Fig. 1, four of such beams are illustrated and they are so spaced that one is adjacent the furnace front, one adjacent the furnace curtain wall 16 and two are disposed in juxtaposition to one another intermediate the first mentioned beams. Hung for longitudinal movement between adjacent pairs of beams are a plurality of tile supports B. The supports each comprise elongated, spaced members 17 of L-shaped cross-section, pivotally carried, as at 17', by means of arms having cross-pieces 18 which span the space between the ledges of the channel irons 13.

Suspended from each support B, by means of hangers 19, are a plurality of abutting tiles 20. The tiles as suspended for each support form a group and the combined groups are in abutting relation considered both laterally and longitudinally of the furnace, see Figs. 1 and 2. With more particular relation now to Figs. 1 to 7 inclusive, each hanger 19 comprises an I-shaped member the upper part of which is adapted to span the space between ledges of a support B and the lower part of which is adapted to enter and co-operatively engage with a slotted and recessed opening in a tile top. As clearly shown in Fig. 6, a tile top is centrally slotted as at 21, the walls of said slot being vertically disposed. Such slot communicates at its bottom with a recess 22 of annular formation. A hanger is first inserted within a tile slot as shown in Figs. 4 and 5 and then moved around its vertical axis 90° so that the lower cross-arm of the hanger engages beneath the ledges 23 formed by a slot and annular recess. Thus interlocked with respect to a tile, a hanger is so positioned with respect to a support that the upper cross-arm of a hanger rests on the lower ledges of said support. Each tile is hung as a unit and the entire roof is movably suspended. Thus the tiles are not rigidly held and stress and strain is eliminated. The side walls 12 of the furnace have shoulders or offsets 12' upon which rest the outmost tiles of each transverse row. Between a tile so located and a vertical wall of the furnace is present a filling 12" of compressible material, as asbestos, in order to permit expansion of the

tiles without undue compression and further provide a gas tight joint. The upper edges of a tile are leveled as at 24 and the space thus formed between abutting tiles is filled with grouting 25 to provide a gas tight joint. 70

The construction shown in Fig. 7, differs from the above construction only in the shape of the support B and its supporting arm.

As shown in Fig. 8, the support B comprises an inverted T-shaped beam 26 suspended from which is a hanger 19 which is also of inverted T-shape. Connecting a hanger and beam are members 27 each clamped to a hanger at one end and flanged 80 to engage over a beam ledge at its other end.

As shown in Figs. 9 and 10 the tiles are suspended directly from the supports B. Each tile is provided with a reduced head 28 having vertical faces and undercut portions 85 29. The flanged portions of the support engage with such undercut portions. By this construction while certain of the tiles cannot be removed without removal of certain other tiles no considerable number of 90 tiles require to be removed to effect repairs.

Common to all the above described types of hangers and tiles is the rear tile supporting structure illustrated in Fig. 1 and in Figs. 11 to 13 inclusive. Resting upon the flanges of each beam B and projected rearwardly therefrom is a member 30 the free end of which terminates in a curtain wall rest 31. Each member 30 is rigidly fixed, as at 32, to a beam and the beam parts are provided with lips 33, with the underside of which lips the bifurcated or forked end of the member engages to prevent depression of the rest 31 under the weight of the curtain wall. The last three tiles of each row are 100 supported by a member 30. Of these tiles, tile 20' is supported by a pair of hangers 19'', the upper ends of which are hook-shaped as at 19' to engage over the flanged portion 34 of a member 30. The meeting faces of tiles 110 20' and a pair of tiles 20'' are cut away as at 37 so as to overlap as clearly shown in Fig. 11, so that in effect the tiles 20'' are seated upon a tile 20'. It will be understood that a pair of tiles 20'' equal the width of a tile 115 20'. In order to maintain tiles 20'' in such seated position two hooks 35 are caused to engage around hangers 19'' and are caused to engage within a recess 36 in the top of a tile 20'' at their opposite ends thereby tying 120 together the three last tiles of each row.

It will now be apparent that I have devised a novel and useful construction which embodies the features of advantage enumerated as desirable in the statement of the 125 invention and the above description and while I have in the present instance shown and described the preferred embodiment thereof which has been found in practice to give satisfactory and reliable results, it is to 130

be understood that the same is susceptible of modification in various particulars without departing from the spirit or scope of the invention or sacrificing any of its advantages.

5. What I claim is:

1. A suspended roof construction of the character stated comprising spaced, transversely disposed, stationary beams, a longitudinally disposed tile support having swinging relation with respect to said beams, a plurality of tiles suspended from said support, means terminating in a curtain wall support carried by said tile support, an auxiliary tile suspended from said means in abutting relation with the first mentioned tiles said auxiliary tile being constructed to support additional tiles, additional tiles supported by said auxiliary tile, and means for maintaining said last mentioned tiles in supported position.

2. A construction as described in claim 1, characterized by said auxiliary tile being provided with a cutaway portion upon which is seated said additional tiles.

25. 3. In a suspended roof construction of the character stated, a tile support, a member projected rearwardly therefrom having transversely disposed ledges, a tile, a pair of hangers detachably secured to said tile and suspended from said ledges, a pair of additional tiles supported upon the first mentioned tile and horizontally disposed hooks each anchored in one of said additional tiles and each engaging around a hanger for supporting said additional tiles in position upon the supporting tile.

35. 4. In a structure of the character stated a combustion chamber including a curtain wall, tiles forming a roof for said chamber,

a support from which said tiles are suspended, a member independent of and detachably secured to and projected rearwardly from said support upon which the curtain wall is sustained, an auxiliary tile supported by said member, additional tiles supported by said auxiliary tile which auxiliary and additional tiles are located beneath said curtain wall and horizontally disposed hooks anchored in said additional tiles for detachably connecting said additional tiles to said auxiliary tile.

5. A suspended roof construction of the character stated comprising a plurality of transversely disposed channel irons arranged in pairs, plates for spacing adjacent channel irons which plates are secured thereto to form therewith a beam, arms depending from each beam each arm having a cross-piece which spans the space between the ledges of a beam, a tile support hung for longitudinal movement between adjacent pairs of beams each tile support being pivoted at its outer end to one of said arms, a plurality of hangers carried by each support and a tile removably carried by each hanger.

6. A construction as set forth in claim 5 characterized by a tile the top of which is provided with a slot communicating with an annular recess for hanger reception and a hanger one end of which is adapted for removable insertion within said slotted and recessed tile and the opposite end of which is adapted for removable connection with said swinging tile support.

In testimony whereof I have hereunto signed my name.

JAY G. THOMAS.
